UNITED STATES PATENT OFFICE.

TRACY V. BUCKWALTER, OF ALTOONA, PENNSYLVANIA.

MOTOR-VEHICLE.

1,240,417.

Specification of Letters Patent. Patented Sept. 18, 1917.

Application filed January 10, 1917. Serial No. 141,516.

• *To all whom it may concern:*

Be it known that I, TRACY V. BUCKWALTER, a citizen of the United States, residing at Altoona, in the county of Blair and State of Pennsylvania, have invented certain Improvements in Motor-Vehicles, of which the following is a specification.

This invention relates more particularly to vehicle frames for use in various ways, but it is designed primarily for use in cars that are self propelled on rails, particularly gasolene section cars.

A chief object of my invention is to provide a strong, convenient and efficient motor driven section car with improved means for effecting its convenient removal from the track, preventing injury to the mechanism when the wheels are off the rails, stopping the car automatically when it has been thrown off the track while running, and protecting the workmen carried from injury by operating mechanism.

A leading feature of my improvements is found in the end truss constructions, which cover the wheels and extend laterally beyond the rails and downward approximately thereto, or so as to have a clearance less than the height of the rails, these trusses being adapted for supporting the car platforms over the wheels and longitudinal foot boards exterior thereto.

The wheels, together with the driving mechanism, are housed by the parts of my improvements, and the car is carried thereon by on the rails when the wheels have been intentionally removed or have accidentally left the track. The car will be stopped by friction between the frame and the rails when it has left the track while running and can be skidded on the rails and removed therefrom readily when desired.

The characteristic advantages of the improvements will be more fully understood from the following description of a special construction embodying the same and the accompanying drawings in illustration thereof.

In the drawings, Figure 1 is a plan view of a car embodying improvements of my invention, with the upper deck member removed; Fig. 2 is a side elevation of the car; Fig. 3 is an end elevation of the same construction mounted on rails, and Fig. 4 is a broken end elevation of the car off the track and supported by the engagement of the end trusses with the rails.

The car illustrated in the drawings is provided with a frame comprising the longitudinal outer sills 1 and inner sills 1' having the form of channel bars, the cross-bars 2 of tubular form fixed on the ends of the sills by clevises 3, the truss struts 4 having the form of angle bars with top extensions 4' fixed to the ends of the sills, the top and bottom truss chords 5 and 6 having the form 60 of angular bars fixed to the suspended uprights 4, the diagonal cross braces 7 connecting the top and bottom chords between the uprights, the diagonal braces 8 having the form of angle bars connecting the end 70 members 4 and the ends of the top chords 5 with the ends of the bottom chords 6, the longitudinal plates or boards 9 fixed to the members 6 and 8 with the aid of the bearings 9', and the longitudinal running 75 boards 10 having their ends fixed to the outer ends of the members 6.

Struts 11, having the form of angle irons, are fixed at their lower ends to the sills 1', longitudinal sills 12 are fixed to the tops of 80 these struts, cross pieces 13 connect the sills, and guards 14 are fixed to the end struts 11 and the cross-beams 13.

Journal bearings or boxes 15, for the axles 16 having the wheels 17 thereon, support the springs 18 by which the sills 1, directly, and the frame are supported. Radius or tie rods 19 and 20 connect the boxes for the respective axles to the sills 1' and end truss members 4, and links 21 connected with the sills 1 pass around the tie rods to limit the upward movement of the frame.

It will be understood that the frame described is adapted to be boarded over to 95 provide platforms for carrying men or materials and a housing for relatively movable parts described (all of which lie within the frame) as well as for the braking parts comprising the shoes 22, the operating rods 100 23 and the retracting springs 24, and the propelling parts comprising the driven sprocket wheel 25 on the axle 16, the sprocket chain 26 which drives the wheel 25, the sprocket wheel 27 which is fixed on 105 the journaled shaft 28 and drives the chain 26, the motor 29 for driving the shaft 28, the fuel tank 30 for supplying the motor, the system 31 for cooling the water, the exhaust mechanism 32, and the compressor 110 34 and the various connections thereof.

The distance between the bottoms of the end trusses, or the chords 6, and the rails 33 is less than the height of these rails. Therefore when the wheels have been removed from or have left the rails, the car can be carried by the engagement of the bottom chords with the rails without the wheels contacting with the ties or ballast, and the trusses of the derailed car will ride 10 on the rails to stop the car by friction, or can be slid on the rails to remove the car from the track.

Having described my invention, I claim:

1. In a car, the combination with means 15 comprising traction wheels and journal boxes therefor, of a frame having depending end trusses extending beyond said wheels and between which said wheels are disposed, said trusses having bottom members whereby said car can be skidded and means for tying together a truss and journal box aforesaid.
2. In a car, the combination with traction

wheels, of means carried by said wheels, 25 said means comprising a frame having depending trusses extending laterally of said car beyond said wheels and running boards extending along said car exterior to said wheels and supported by said trusses.

3. In a car, the combination with traction 30 wheels, of housing means comprising depending end trusses extending laterally of said car, side foot boards and a superstructure.

4. In a car, the combination of carrying 35 and housing means comprising end trusses, side boards, side platforms, and an elevated platform between said side platforms providing a housing for motor mechanism for driving said car, of traction wheels operable 40 by said motor mechanism and protected by said trusses, boards and side platforms.

In testimony whereof I have hereunto set my name this 5th day of January, 1917.

TRACY V. BUCKWALTER.
